RAZOR BLADE KNIFE

James C. Stineman, 1230 Grove St., Clearwater, Fla.
Filed July 25, 1961, Ser. No. 126,711
1 Claim. (Cl. 30—339)

This invention relates to utility cutting knives and more particularly to a sectional knife using a removable safety razor blade as the cutting implement.

The invention broadly comprises an elongated knife with a body formed of two sections of spring steel, adjacent ends of the sections being shaped to removably receive and clamp a safety razor blade therebetween.

A principal object of the present invention is to provide a utility cutting knife having a removable safety razor blade as the cutting implement.

Another object of the invention is to provide an elongated utility cutting knife with a sectional body so that a safety razor blade of varied construction may be readily clamped therebetween in operative position.

A further object of the invention is to provide an elongated utility cutting knife with a sectional body having means at one end for releasably mounting a safety razor blade and having means at the other end for releasably clasping the sections of the body together with a snap action.

Still another object is to provide a sectional utility cutting knife that is simple and rugged in construction, economical to manufacture and attractive in appearance.

It is also proposed, according to a modification of the invention, to provide a utility cutting knife with a sectional body wherein the sections are hingedly connected together.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

FIG. 1 is a top plan view of a knife embodying one form of my invention.

FIG. 2 is a side view of the knife, with the blade removed.

FIG. 3 is a view similar to FIG. 2 but showing the sections of the knife body separated.

FIG. 4 is a top plan view of the bottom section of the knife body as viewed in FIG. 2.

FIG. 4A is a plan view of the cutting element.

FIG. 5 is a longitudinal sectional view taken on the line 5—5 of FIG. 4.

FIG. 6 is a bottom plan view of the top section of the knife.

FIG. 7 is a longitudinal sectional view taken on the line 7—7 of FIG. 6.

FIG. 8 is a top perspective view of the blade latching mechanism per se.

FIG. 8A is a side elevational view of a rivet.

FIG. 9 is a top plan view of the razor blade supporting end of the bottom section of the knife showing a blade in cutting position.

FIG. 10 is a top plan view of the razor blade supporting end of the knife.

FIG. 10A is a plan view of the cutting element.

FIG. 11 is a fragmentary side view of parts of a joint, in spaced apart relation, of a sectional body of a modified form of cutting knife.

FIG. 12 is a top plan view of the parts of FIG. 11 in assembled relation.

FIG. 13 is a side view of the parts of FIG. 12.

Referring in detail to the drawings, in FIG. 1 a utility knife made in accordance with the invention is shown and

2

designated generally by the reference numeral 10. The knife is formed of two separable complementary sections 20 and 22 which when superimposed one upon the other define the complete knife 10. Each section has a rectangular-shaped, flat, plate-like body portion and an elongated shallow shell-like handle portion, arcuate shaped in cross section and rectangular-shaped in plan.

The body portion of section 20 is designated 27 and the handle portion 24. A shallow rectangular-shaped recess 28 is formed in the inner surface of the body portion at the center thereof. The outer free end of the body portion is cut away to provide a clearance 30. A latch 25 is formed integrally with the outer free end of the handle portion 24. Latch 25 extends outwardly in the direction of the end of the handle portion and then extends slightly radially of the handle portion forming a prolongation of the handle portion and serving as a finger piece. The peripheral edge 26 of the handle portion 24 is flat. A lug 38 is formed integrally with the body portion 27 at its junction with the handle portion 24. The lug extends outwardly of the plane of the edge 26 of the handle portion 24 and serves as a guide to center the sections in assembling. The flat peripheral edge 26 of the handle portion 24 is on a plane with the body portion 27.

In section 22, the body portion is designated 39 and the handle portion 24a. The flat peripheral edge 26a of the handle portion is on a plane with the body portion 39. At the outer free end of the handle portion, a notch 31 is formed to receive the latch 25, the edge wall of the notch coacting with the clip to interlock the sections. A shallow central recess 40 is formed in the inner surface of the body portion 39. A pair of spaced aligned openings 43 are formed in the body portion 39 centrally thereof and a hole 48 is formed between the openings in line therewith. A shallow flange 50 is formed on the outer free end of the body portion and ends remote from the sides of the body portion so as to be received in the clearance 30 in body portion 27 of section 20. A shallow recess 54 is formed in the body portion 39 at its junction with the handle portion 24a so as to accommodate the lug 38 in assembled condition.

In accordance with the invention, a rectangular-shaped spring metal plate 42 is fastened to the bottom or outer surface of the body portion 39 of section 22 by means of a rivet 45 extending through a central opening 46 in the plate and the hole 48 in the body portion 39. A pair of aligned short lugs 44 is suitably secured to the plate 42 on one surface thereof adjacent its ends. The lugs are preferably tapered along one side as indicated at 43, and extend through the aligned openings 43 in the body portion 39 and extend slightly inwardly of the plane of the body portion so as to provide short protuberances. The inherent flexibility of the material of the plate 42 is such that it can be bent to swing the lugs 44 through the openings 43 outwardly to the plane of the body portion to eliminate any protuberant portion of the lugs when desired.

The knife can be used with safety razor blades of ordinary construction having double edges, or can be used with safety razor blades of ordinary construction having only a single cutting edge. In the knife shown in FIG. 1, a thin double edge blade 69 of the Gillette type having a continuous cutout portion 62 along the center thereof extending approximately the length of the blade is shown clamped between the body portions 27 and 39. In assembling the knife, the blade is placed on the upper surface of body portion 39 with the protruding lugs 44 received in and extending through the cut-out portion 62 of the blade. The section 20 of the knife is then superimposed on section 22, the lug 38 riding in recess 54 and tending to center the sections. Pressure on the free end of section 20 against the free end of section 22 snaps the

latch 25 into interlocking engagement with the edge walls of the notch 31 thereby clamping the body portion 27 against the blade 63 and against the body portion 39 thus securely holding the blade in cutting position with its cutting edges on both sides of the body portions as seen in FIG. 1. The sections of the knife can readily be pried apart when it is desired to renew the blade. The elongated handle portion of the knife affords the necessary leverage for effective use of the knife.

The knife 10 can also be used with a safety razor blade of ordinary construction of the single cutting edge, such as the blade 49 shown in FIGS. 9 and 10. The blade 49 has a thin flat body rectangular in shape with a cutting edge 51 along one long edge and a reinforcing strip or clip 53 along the other long edge on both sides thereof. In assembling the knife with this type of blade, the blade is placed flatwise on the top surface of the body portion 39 of section 22 with its reinforcing strip portion 53 over the lugs 44 and in line with the central recess 40, with the body of the blade overhanging one long edge of the body portion 39 and with the cutting edge 51 projecting outwardly of said body portion. Section 20 is then superimposed on section 22 with the body portion 27 of section 20 engaging the blade 49 whereupon inward pressure is exerted upon the section 20 so that the blade forces the lugs 44 through the openings 43 in the body portion permitting the blade to become seated upon the inner surface of body portion 39 and clamped thereagainst. At the same time, the clip 25 snaps over the edge walls of notch 31 holding the sections together and the blade in cutting position.

The invention also contemplates a sectional knife wherein the sections of the knife, at the ends of the body portions, are hingedly connected together in order to offer somewhat greater convenience to the user in opening and closing the knife. A fragment of such a modified form of knife 10^a is shown in FIGS. 11 to 13, inclusive. In this form, the body portion 27^a of section 20^a is formed at its free end with a tubular hinge knuckle 70. The free end of the body portion 39^a of the other section 22^a is formed with a pair of spaced tubular hinge knuckles 72 adapted to receive the knuckle 70 in the space therebetween and in alignment therewith. A hinge pin 74 is journaled in the aligned knuckles for hingedly connecting the sections together.

The knife 10^a is similar in all other respects to the knife 10 and similar reference numerals are used to indicate similar parts.

While I have illustrated and described the preferred embodiments of my invention, it is to be understood that

I do not limit myself to the precise constructions herein disclosed and that various changes and modifications may be made within the scope of the invention as defined in the appended claim.

Having thus described my invention, what I claim as new, and desire to secure by United States Letters Patent is:

A sectional cutting knife comprising a pair of complementary sectional members, each member including a shallow shell-like handle portion rectangular in plan, and a flat rectangular plate-like body portion, said handle portions superimposed in abutting relation defining a hollow handle, said body portions superimposed in closely spaced relation, one of said body portions having spaced aligned openings therealong, a spring plate secured to the outside surface of the perforated body portion, lugs carried by the spring plate and extending through the openings in said body portion to the space between the body portions, and a flat double edge plate-like cutting blade having spaced openings therein clamped in the space between the body portions with its openings sleeved around the lugs, the cutting edges of the cutting blade extending longitudinally of the superimposed body portions, one of the body portions having a recess therein at the juncture thereof with the handle portion, a projecting lug on the other body portion at the juncture thereof with the handle portion adapted to be received in the recess in the other body portion for guiding the sections to assembled condition, one handle portion having a notch at one end thereof, and a latch on the adjacent end of the other handle portion received in said notch and interlocked with the edge walls thereof, one of said body portions having a cut-away portion in its outer free end edge, the other of said body portions having a flange along its free end edge adapted to be received in the cut-away portion of the other body portion whereby said adjacent ends are interlocked to each other.
